(57) **CLAIM**

The ornamental design for a golf glove, as shown and described.

DESCRIPTION

FIG. 1 is a top plan view of a golf glove with connectedly sewn 4th and 5th fingers according to the present invention to assist in maintaining a united grip at the top of the back swing;

FIG. 2 is a bottom or palm view thereof;

FIG. 3 is a right side view thereof;

FIG. 4 is a left side view thereof;

FIG. 5 is a rear view thereof; and,

FIG. 6 is a front view thereof.

The broken lines on the glove are understood to represent stitching.

The fragmentary crosshatched pattern shown in the drawing is understood to represent fabric and is repeated uniformly throughout the areas shown.
